UNITED STATES PATENT OFFICE

2,490,059

TRAVELING ROCKING HORSE

Maurice D. Jacobs, Long Island, N. Y.

Application September 27, 1945, Serial No. 618,929

1 Claim. (Cl. 272—53)

1

This invention relates to rocking devices, in general, and has for its main object to provide a device of this nature, which will advance or travel through novel, efficient means, when it is set into rocking motion. My invention particularly relates to rocking horses, whether toys or exercising devices, and whether for children or adults, which will have substantially the same construction and appearance as hobby horses are constructed and appear now, but which will be caused to travel when rocked by said novel and efficient means.

Another object of my invention is, to provide a device, like a rocking horse, having a runner or rocker member with curved lower contour, which will be divided into a front and a rear part, an interconnection being provided between the two parts whereby a backward rocking will cause the front part of said runner to advance relatively to the rear part, and a forward rocking of the device will cause the rear part to travel forwardly and close upon the advanced front part.

Still other objects of my invention are: to provide a rocking and travelling device of the nature indicated, which may be converted into a stationary rocking device, if desired, and in which means are provided to ease the forward sliding or closing of the rear portion, which carries the user of the device, and which, while rocking and advancing, may also be caused to turn.

Still further objects of this invention will partly be pointed out or will be apparent as the specification of the same proceeds, and, among others, I may mention: to provide a device, as characterized hereinbefore, which will be adapted for smooth and continuous rocking and rolling motion while the same is advancing; which will be simple in construction, strong and reliable, comparatively inexpensive to manufacture, and will have very few moving parts, which will be quiet and safe in operation, preventing a possible injury to a child using the same, and which may move on almost any kind of ground or floor, rugs, lawn, etc., indoors or outdoors.

In the drawings, forming a part of this specification and accompanying the same:

Fig. 1 is a side elevational view of the preferred embodiment of my invention, as applied to a rocking horse;

Fig. 2 is a plan view thereof;

Fig. 3 is a diagrammatic view of a runner used in my invention and formed of two parts;

Figs. 4, 5 and 6 are diagrammatic illustrations

2

of the relative movements of the parts of the runner upon rocking the same;

Figs. 7, 8 and 9 are detailed sectional views, the sections being taken on the lines 7—7, 8—8, and 9—9, respectively, of Fig. 1.

Figs. 10, 11 and 12, are fragmentary side, plan and sectional views, respectively, of a modification of my invention, and

Figs. 13, 14 and 15 are similar views of still another form of embodiment thereof.

Fig. 16 is a semi-diagrammatic elevational view of a further embodiment of my invention, and

Fig. 17 is a sectional view thereof, the section being taken on the line 17—17 in Fig. 16.

Referring now to the drawings more in detail, by characters of reference, in Figs. 1 to 9 the numeral 30 indicates said preferred embodiment of my invention, as applied to a rocking horse, in general, the numeral 31 indicating the runners or rockers of the same, and the numeral 32 the upper structure, or horse.

The runner or rocker portion 31 is composed of two plate-like edge-wise set members 33 and 34, each having an arcuate lower or rocking edge 35, and, in the embodiment shown, a straight upper edge 36. Each runner or rocker, however, is composed of a rear member 37 and a front member 38, the two substantially forming a plate of the shape of the respective whole runner 33 and 34, but being separated by an arcuate slot 39, said slot preferably being arranged in the front part of the device at a distance above the lower or bottom edge 35a of said front member, and being in parallelism therewith. The total separation of the two members is effected by a transverse terminal division or slot 40 between the two members at the rear end of the front member 38.

It will be seen that the front member reaches quite a distance towards rearwardly, preferably beyond the center line of the device, while the upper portion of the rear member 37 reaches considerably forwardly, its front end being indicated at 41. Forwardly from the upper end of the separation line, or from said front edge 41 of the rear member, the upper horizontal side of the runner or rocker device is formed by the front part thereof, as indicated by the numeral 36a.

Two transverse plate members, 42 and 43, may be secured across the rear members 37 of the two runners, at a desired distance from one another and upwardly inclining towards one another, and the rocking horse 32 may be built on

these two cross members 42 and 43 in the manner indicated in the drawings, or in any other appropriate manner, its front leg 43a being placed quite forwardly, as well as the saddle 44, receiving the weight of the user, also preferably will be placed quite forwardly of the rear runner. In the embodiment shown, the head and neck of the horse is formed by a vertical plate member shaped as shown, and having the grips or handles 45 secured thereto.

An elongated vertical outer plate 46 is secured on the forward end of the rear portion 37 of each runner, as indicated at 47 and 48, the plate 46 being lower than its securing upstanding lugs 47 and 48, covering most of the respective front runner member 38, but at most of its length being somewhat narrower than the said front member, so as not to touch the ground. The narrow portion is indicated at 46a. Said plate 46, however, is extended rearwardly, to a slight distance beyond the said transverse separation line 40, and the rear portion 46b thereof will be made somewhat wider downwardly to be in registering relation with the bottom, or rocking, edge 35 of the rear member 37 of the runner device.

An elongated curved front slot 49 and a similar elongated curved rear slot 50 are cut through the material of the front runner member 38, said slots also being in parallelism with the bottom or runner edge 35a thereof.

A roller 51 is arranged in the front slot 49, and a similar roller 52 in the rear slot 50, said rollers running on pins secured into the outer plate 46, which plate is secured on, and depends from, the rear member 37 of the runner, as has been mentioned hereinbefore. The rollers 51 and 52, therefore, are adapted to ride in the slots 49 and 50 independently of the front member 38, as required by its relative movements with reference to the rear member 37. To further secure and stabilize the rollers 51 and 52, inside depending members 51a and 52a may be secured on the forward part of the rear member 37 and the inner ends of the pins for the rollers secured in them, as will be understood.

Finally, I also may secure an inwardly extending pin 53 on the rear part of the front member, and a pin 54 on the depending inside element 52a on the rear runner member 37, and a rubber spring 55 will be arranged between pin 53 on the front member and pin 54 on the rear member. Obviously, the end on pin 54 of the spring will be forwardly with reference to its end secured on the pin 53.

In Figs. 4 to 6, I illustrate in a diagrammatic manner, the method, or manner, by which my device will automatically advance upon the rocking of the same.

In Fig. 4 I show the runner device in a normal resting position, and it will be seen that the rear member 37 thereof is closed on the front member 38, rollers 51 and 52 being at the forward ends of their respective curved slots 49 and 50, and the spring member 55 being stressed and expanded, pin 54 pulling its respective end forwardly when the rear member 37 closes on the front member 38.

Suppose that in this situation the device now is rocked backwardly, as indicated by arrow 56 (Fig. 5). When the backward rocking reaches to such an extent that the device entirely is resting on the rear member 37, the front member 38 will be released from its frictional binding on the ground, and will shoot forwardly, as indicated by arrow 57, spring 55 pulling the same in that

direction, since the forward end of the spring on pin 54 will be stationary and locked on the rear member, while the rear end, on pin 53, now is free to move forwardly, under the tension in the spring.

The final position after this movement, will be the one indicated in Fig. 5 whereby the front member 38 will shoot forwardly and upwardly, beyond and above the front edge 41 of the rear member 37 to a distance allowed by the slots 49 and 50, and the spring 55 will contract into a normal condition. Rollers 51 and 52 will ride in the slots 49 and 50 up to the rear ends thereof.

When, now, the rocking device is rocked forwardly, as indicated by the arrow 58 (Fig. 6), and to such an extent that the weight of the device will rest entirely on the forward rocker member 38, the rear member 37 will be released from a binding on the floor, and will slide forwardly on the front member on the rollers 51 and 52 in the respective slots under the weight of said rear member, itself, and possibly that of the user, if the rocking device is a hobby horse. Such a forward sliding of the rear member will continue until it closes upon the front member, and the spring 55 will, again, be stressed or expanded through this movement, as indicated in Fig. 6.

It will be seen, however, that through said backward and forward rocking, the device advances in a straight direction with the extent of the forward shooting of the front runner member 38. Upon each rocking, backwards and forwards, the same advance will be made, and in this manner, the device will travel while rocking.

It will be seen that upon a forward shooting of the front member 38, the wider rear portion 46b of the outer plate 46, secured to the rear member 37, will cover the gap between the rear end 40a of the front member and the edge 40b of the rear member corresponding to the same, and since the lower edge 46c of said rear portion 46b is a continuation of the general bottom or rocking curve 35 of the device, the backward and forward rocking will be smooth and continuous, without any shocks or jars.

It also will be obvious that upon a forward rocking to a suitable degree, the part 46b also will be released from a binding with the ground, and will permit a forward sliding of the rear portion 37. Its continuous smooth forward and rearward rocking will also enable my device to be used on practically any ground, not only on a smooth floor but also on a carpet, in the open air, on lawns, etc.

In my invention means are also provided whereby my travelling rocking device may be changed to a plain rocking device, without the advancing or travelling feature, when desired.

For this purpose the two members 37 and 38 of the rocker will be temporarily locked to one another, whereby an advance shooting of the front member 38, and a consequent closing thereon of the rear member 37, will be prevented. One embodiment of such a means is shown in

Figs. 1, 2 and 9, and is generally indicated by the numeral 60. In this embodiment, for the purpose in view, a comparatively wide vertical hole or recess 61 will be formed in the forward part of the rear runner 37, above and over the front runner 38. Said larger recess or hole will be continued downwardly through the material of the rear runner 37 by a narrower hole 62, and, similarly, it will be continued upwardly, opening into the top of the rear runner, through another 75 similar narrower hole 63.

A pin 64 will be placed slidably through the narrow holes 62 and 63, and a disk 65 will be secured on said pin in the wider recess 61. A coiled spring 66 will be inserted around the pin 64 between the bottom of the recess 61 and the disk 65. A receiving hole or recess 67 also will be provided in the upper edge of the front member 38 opposite to the pin 64 in the rear member.

It will be obvious that, normally, the spring 66 will push said pin 64 upwardly, and its lower end 68 will be out of engagement with the recess 67 in the front member 38 and said front member will be permitted to slide forwardly with reference to the rear member. If, however, it is desired to lock the two members and change the travelling device to a plain rocking device, the user of the hobby horse will step on the upper end of the pin 64 and will press it downwardly, against the spring 66, whereby the lower end 68 of the pin 64 will engage the recess 67 in the front member and the two members will be locked to one another as long as the pressure of the foot on the pin 64 is maintained.

It will be seen that if both sides of my device are locked in the manner described, the user stepping on the locking pins 64 in both runners by the respective feet, my device is turned into a usual rocking horse with no advancing feature.

However, if only one runner of my device will be locked in the manner explained hereinbefore, like for instance, stepping on the locking pin 64 on the right hand side of my device only, then it has been my experience that upon the rear part trying to close on the front parts the device will turn in the direction indicated by arrow 69, that is, toward the locked side, in this instance toward the right. It seems, that in this case the part of the bottom or rocking edge 35 of the right hand locked runner, resting on the ground, as indicated at 70, will serve as the turning or pivot point, and the left side of the device will travel in a circular path therearound, as indicated at 71.

It also has been my experience that even if one side runner is locked, still the rear part of the runner may close on the front part in the other runner, in this case in the left hand side of the device, not locked. This I attribute to the comparatively great weight of the rear part with the user, the child, thereon and the leverage action thereof on the swivel center 70 in the locked right hand runner.

The locking device 60 may take any other appropriate form different from the one shown and described, and a device according to the idea of the locking means 60 may be made independently of the runner, as for instance, in a separate housing, and then secured on the runner, instead of being formed in a recess in the material thereof.

The slot and roller co-action between the rear and front parts of my device may also be constructed in a great many ways, different from the ones shown, but without departing from the scope of my invention.

Instead of the plain rubber springs 55, other stretching resilient elements, like coiled springs, may be used, and they, as well as the rollers may be concealed within the respective parts of the device.

My invention also provides an advancing rocking horse which is entirely safe, and even small children may play with it without any danger of injury, as has been mentioned, the rocking and advancing of a device constructed according to

my invention will be smooth, uninterrupted, continuous, without any jars or shocks, and it may operate in such a desirable manner on almost any ground, and not only on the usual smooth floor of a room.

My invention obviously also provides an advancing rocking horse which is very simple in construction, comparatively easy and inexpensive to manufacture, and still reliable and durable in use.

In Figs. 10 to 12, I show a modification in the construction of my two part runners or rockers.

In this modification the rear runner part is indicated, in general, at 80, and the front part at 81. The horse part of the device is shown as broken away in the drawings, being only indicated at 82, and its securing into and on the rear parts of the two runners at the two sides of the device is indicated at 83 and 84, as will be understood.

The front part, generally indicated at 80a of the rear runner portion is forked having the two branches 85 and 86a between which is arranged the front runner portion 81. Slots 86 and 87 are formed in the front portion 81 and rollers 88 and 89 are in said slots, said rollers being secured in the rear portion of the runner as indicated at 90 and 91.

A small plate 92 is secured across the front, forked, part 80a of the rear runner 80, carrying the pin 93, and a corresponding pin 94 is secured adjacent the rear end of the front runner portion 81. A rubber spring 95 is secured between the two pins.

The use and operation of this type of runner will be similar to those described hereinbefore.

Upon a rear rocking, the spring 95 will pull the front member 81 forwardly to the limit allowed by the slots 86 and 87. Upon a reverse, forward rocking, the rear member 80 will close upon the front member, again to the limit of the slots, and, in this manner, rocking and advancing will be produced in a simple attractive looking device.

Another modification of my invention is shown in Figs. 13 to 15.

In this embodiment, the rear runner portions are indicated at 100 and 101, respectively, which are interconnected by the frame structure 102 on which is built the upper part 103 of the device. This part may, again, imitate a horse, but preferably some other animal adapted to have the long forward neck portion 103a.

The two forward runner members 104 and 105, may be used in this embodiment, too, but they are shown as placed inwardly of the rear portions 100 and 101, and as suspended from the neck 103a. Said neck may have a long appropriately curved slot 106 formed therethrough, in which may run the rollers 107 and 108, secured in the upper portions 104a and 105a of the front runner members 104 and 105.

In the front end of the neck 103a is secured the downward pin 109, and a corresponding but upward pin 110 is secured on the frame member 111 connecting the two front members 104 and 105.

A rubber spring 112 is secured to the two pins 109 and 110, and it will be seen that the use and operation of this form of my invention is similar to those described hereinbefore.

Upon a rearward rocking, arrow 113, the front members 104 and 105 will shoot forwardly, arrow 114, under the influence of the rubber band 112 and to the limit defined by the front end 106a

of the slot 106. Upon a forward rocking (arrow 115), the front members will be fixed on the floor and the rear runner or rocker members 108 and 101 will slide forwardly, under the force of gravity (arrow 116), to the limit allowed by the slot 106, as indicated in Fig. 13 at 106b.

This form of my device is particularly adapted to imitate a desired animal, advancing with its forward legs upon every rearward rocking.

In Figs. 16 and 17 I show still a further modification of my invention. This modification embodies the principle that the user, like a child, of the rocking device or rocking horse, may have means right on the upper part, or on the rocking horse proper, whereby at will may lock either the right or left hand side of the device, as has been described hereinbefore, but instead of two independent operating locking means being provided, like the slideable pins 64 in the earlier embodiment of this principle, one single element, adapted to be easily available to the user of the device, like a child sitting on the horse, will operate either locking devices as desired.

In the embodiment of Figs. 16 and 17 this single means is in the form of a swivelled or rotatable head 120 for the horse, which has means depending therefrom, whereby upon a right turning it will lock the right hand side of the device, and upon a left turning it will lock the left side rear and front runner members to one another.

The embodiment of Figs. 16 and 17, generally follows the one shown in Figs. 1 and 2, and for this reason certain parts thereof have been omitted to clearer show the novel principle illustrated in Figs. 16 and 17. In this embodiment, also, two runners or rockers proper, 33 and 34, are employed, each being composed of a rear member 37 and a front member 38, separated by the slots 39 and 40, and operating in an identical manner as has been described in connection with the embodiment of Figs. 1 and 2. In this embodiment, however, the head 120 of the horse is separate from the upper structure 32 of the device, and is rotatable thereon, having a depending shaft or rod 121 secured thereto which is rotatable in an appropriate hole or bearing 122 in said upper structure 32.

It will be seen that upon a right hand or left hand turning of the horse's head 120, by the child sitting in the saddle 44, and using the handles or grips 45 in the horse's head, the shaft 121 will rotate or rock to the right or to the left.

At the lower end of the shaft a forwardly projecting rod 123 is secured, having at its forward end a transverse right hand branch 124 and a left hand similar branch 125. A flat spring 126 may be secured on the right hand rear runner and a similar spring 127 may be secured on the left hand rear runner member in the manner to be described presently.

The springs 126 and 127 are secured at their inner ends on the rear runner 37 of each side, as by securing the said springs on the inner downward plates or members 52a on the respective sides above the pins 54 carried by said members for the rubber springs 55 as has been described hereinbefore.

As will be seen from the drawings, the springs are set low enough to reach, with their free ends 126a and 127a, the front runner members 38. Normally the springs are spaced apart from said runner members, as indicated in Fig. 17. When, however, the horse's head is turned to the right, it will cause the depending rod 121 also to turn in a right hand direction, as indicated by the arrow 128 causing the T-shaped bottom rods 123, 124, 125 to rotate in the same direction (arrow 129). This movement will cause the right hand branch of said lower rod system to press against the free forward end 126a of the spring 126, pressing said spring against the right hand front runner member 38, as will be understood.

As long as the horse's head is turned to the right with sufficient force, it will press spring 126 against said runner member and prevent its operation, whereby the right hand rear and front runner members will be temporarily locked to one another.

It will be seen that the right hand runner member is not operating now for advancing the device, wherefore the device will turn on said locked member (arrow 130), as has been explained hereinbefore, in connection with the embodiment of Figs. 1 and 2, and the operation of the locking pin 64 therein.

When the right hand turn and pressure on the horse's head is released, the spring 126 will also be released, and the locking effect between the rear and front right hand runner members will terminate.

On the other hand, obviously, if the horse's head is turned to the left, an identical operation is produced on the left hand side of the device through the rod member 125 and spring 127 (arrow 131), and the left side rear and front runner members will be locked whereby the device will be caused to turn to the left, as shown by arrow 132.

In a word, the user, like a child, of the rocking horse, can simply guide the horse to the right or left by pulling the horse's head to the right or left.

To increase the effect of the springs, the parts of them pressed by the respective rods 124 and 125, may be curved outwardly as at 126b and 127b, and the respective portion of the front runner member 38 may even have a recess to receive that outwardly bulging portion of the spring and thereby effect a more secure binding between the spring and the front runner member.

It will thus be seen that there is provided a device in which the several objects of this invention are achieved, and which is well adapted to meet the conditions of practical use.

As various further possible embodiments might be made of the above invention, and as various changes might be made in the embodiments above set forth, it is to be understood that all matter herein set forth or shown in the accompanying drawings is to be interpreted as illustrative and not in a limiting sense.

What I claim as new and want to protect by Letters Patent of the United States, is:

In an advancing rocking device, a rocker or runner having a continuous single curved lower rocking edge whereby to rock the device on an appropriate supporting surface, like the floor in a building, said runner being composed of a front and a rear member, means to mount said members for movement one relative to the other, said front member being prevented from moving forwardly, in the normal position of the rocker, down to contact of said front member with the supporting surface, said front member being adapted to be entirely freed of the supporting surface upon a predetermined rear rocking of the device, the device then being supported entirely on said rear member, and said rear member being similarly adapted to be entirely freed of said surface upon a suitable forward rocking, the device then being entirely supported on said front member, means

adapted to cause said front member to move forwardly upon such a rearward rocking of the device, and means to cause said rear member to move forwardly and close on said front member upon said forward rocking, two such runners being provided in the device, their rear members being interconnected, but the front members being independent of one another, normally inactive independent means between the two members for each runner for locking them to one another, the means for locking the two members of one runner being independent of the means for locking the two members of the other runner, thereby to cause the device to turn in a right hand or left hand direction as desired.
